UNITED STATES PATENT OFFICE.

NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,182,338.

Specification of Letters Patent.

Patented May 9, 1916.

Application filed May 7, 1910. Serial No. 559,396.

To all whom it may concern:

Be it known that I, NILS H. ANDERSON, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to 10 which it appertains to make and use the same.

This invention relates to ribbon mechanism for typewriting machines, and with 15 regard to the more specific features thereof, to ribbon spool construction.

One of the objects of the present invention is to provide a simple and practical device of the above character, having few parts, which will be cheap to manufacture, 20 easy to assemble and efficient in use.

Another object is to provide a device of the above character which will be simple in construction, enabling a ribbon to be quickly placed upon or removed from the 25 ribbon spool.

A further object is to provide mechanism of the above character in which the cover of the ribbon spool or reel is not likely to become wedged in engagement therewith.

30 A further object is to provide a self-contained ribbon spool, that is, one in which both heads and hub will rotate together as a unit, and allowing for the assembling or disassembling of the ribbon conveniently 35 and efficiently in the coil form in which it is supplied by the manufacturers.

Other objects will be in part obvious and in part pointed out hereinafter.

This invention accordingly consists in the 40 features of construction, combinations of elements and arrangement of parts which will be exemplified in the construction hereinafter set forth, and the scope of the application of which will be indicated in the 45 following claims.

In the accompanying drawing, wherein 50 is shown one of various possible embodiments of this invention, Figure 1 is a vertical sectional view of part of a typewriting machine sufficient to illustrate one embodiment of the present invention as applied thereto; Figs. 2 and 3 are detail views of various parts.

Similar reference characters refer to simi-

lar parts throughout the several views of 55 the drawing.

While the present invention is herein shown and described with reference to a construction adapted for use with the narrow ribbon for visible typewriters, and more 60 particularly to the ribbon mounting employed in a noiseless typewriting machine, it is understood that the invention may be applied to other forms of machines employing either a narrow or broad ribbon if so 65 desired.

When a ribbon spool is mounted to rotate on its driving shaft, and retained in place thereon by a nut threaded on the shaft, a slight space is preferably provided between 70 the loosely mounted spool-head and the nut, otherwise the friction between the head and the nut will interfere with the rotation of the spool. Notwithstanding this precaution, the uneven winding of the ribbon upon the 75 spool will frequently raise the spool-head until the space referred to is eliminated and the objectionable friction will then ensue, as the nut will act as a drag or brake opposing the rotary motion of the spool, and 80 in some machines interfering with the efficient operation of the carriage. For this reason, a construction such as will be hereinafter described is desirable.

Referring to the drawing in detail, 1 represents a rotary driving spindle or support 85 surrounded by a stationary ribbon cup 2 resting on the frame 3 and surrounding the lower part of a ribbon spool. This spool comprises a central hollow hub 4 having secured thereto a supporting plate 5 loosely mounted upon the spindle 1 and provided at the lower part thereof with a gear 6 adapted to mesh with a driven gear 7, which in turn meshes with a gear 8 fast on the driving 90 spindle. The gear 7 is adapted to be thrown in and out of mesh with the gears 6 and 8 simultaneously with the action of a corresponding or similar ribbon mechanism at the opposite side of the machine, for the 95 purpose of reversing the feed of the ribbon, but as this mechanism forms no part of the present invention a further description thereof is unnecessary.

Carried by a hollow cylindrical hub 4 are 100 a plurality of flat spring arms 9, such as shown in the detail view, Fig. 3, having hook shaped ends 10 projecting above the

upper part of the hub adapted to engage a plurality of crescent shaped openings 11 in a cover plate 12, whereby the cover plate may be snapped into operative relation with the hub by a downward movement thereof. The cover plate 12 is preferably provided with a hollow central boss 13 having a central opening therein adapted to be engaged by the upwardly projecting reduced end 14 of the driving spindle 1. This projecting end is preferably rounded whereby the cover may be quickly centered in order more readily to engage the spindle when applied thereto. The boss 13 is preferably knurled about its periphery at 15 whereby the same may be firmly grasped by the operator when handling the same.

In operation, when it is desired to change a ribbon 16 passing through a slot 17 in the cup 2, which is preferably mounted on a ribbon core 18 adapted to surround the hub 4, the cover 12 is removed by an upward pull on the boss 13 whereby the same becomes readily disengaged from the spring arms 9. The ribbon 16 and core 18 may then be slipped off the hub 4 and a new ribbon mounted thereon, after which the cover 12 is slipped over the projecting end 14 of the driving spindle and pressed downwardly until the hook shaped ends 10 snap into operative relation with the holes 11 in the cover plate.

It is thus seen that this invention provides for a simple and practical device allowing the operator to quickly change the ribbon and also overcomes the objection common in ribbon mountings where the cover has a threaded connection with the spool or spindle and is likely to become tightly wedged thereon during the operation of the machine.

As many changes could be made in the above construction and many apparently widely different embodiments of this inven-

tion could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In a ribbon mounting, in combination, 60 a rotatable support, a spool carried thereby having a hollow central hub, a cover for said spool adapted to abut the end of said hub, and spring arms carried by said spool engaging said cover.

2. In a ribbon mounting for typewriting machines, in combination, a rotatable shaft, a disk ribbon support thereon having a hub about said shaft, spring fingers on one of said parts projecting upward beyond said hub, and a disk cover having a recessed boss to fit over said shaft and frictionally engage said fingers.

3. In a ribbon mounting for typewriting machines, in combination, a rotatable shaft, 75 a disk ribbon support thereon having a hollow hub about said shaft, spring fingers on one of said parts projecting upward above said hub, and a disk cover having an apertured boss to fit over said shaft and compress said spring fingers to maintain frictional attachment of said cover.

In testimony whereof I affix my signature in the presence of two witnesses.

NILS H. ANDERSON.
